UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

ELECTRIC CONTROLLER.

Original application filed June 14, 1918, Serial No. 240,035. Divided and this application filed June 14, 1922. Serial No. 568,337.

This invention relates to electrical controllers for mining and other machines, and has for an object the provision of an improved controller of this character having 5 means for reducing the sparking or arcing within the apparatus during the operation thereof and for minimizing the effect of such sparking or arcing.

In the accompanying drawings I have for 10 purposes of illustration shown one form which my invention may assume in practice.

In these drawings:—

Fig. 1 is a front elevation of a controller box constructed in accordance with the invention.

Fig. 2 is a transverse section taken on the line 2—2 of Fig. 1, looking in the direction of the arrows seen thereon, and showing the fuse plug locked against removal and the 20 controller handle unlocked.

Fig. 3 is a section on the line 3—3 of Fig. 1, showing the means for positioning the controller handle.

Referring to the drawings, 1 denotes a 25 part of a controller box or casing containing a plate 3 secured to and spaced from the front wall of said casing by means of bolts 30 and spacing sleeves 37, respectively. Suitably attached, as by bolts 2, to one face 30 of the plate 3, is an insulating casing 6 containing a hollow line terminal 5 disposed opposite an opening 32 in the plate. On the opposite face of the plate 3 is a series of contacts 7 conveniently arranged in an arc of 35 a circle and between which and said plate is preferably interposed an insulating lining 8. A brush 9 is adapted to wipe over the contacts 7, said brush being slidably mounted in a head 11 and being pressed toward said 40 contacts by a spring 33 interposed between said brush and a follower 34 which engages an insulating lining 36 secured to the front wall of the casing 1. The head 11 is connected by an arm 13 with a terminal 15 in 45 axial alinement with the line terminal 5. The arm 13 and terminal 15 are secured, as by bolts, 12, to an insulating plate 17, the later in turn being secured, as by bolts 14, to a collar 19 of a hollow shaft 21 arranged 50 coaxial with the terminals 5 and 15 and journaled in an opening in the casing 1. Secured to the plate 17 by the bolts 14 is an insulating shield 16 which encloses the terminal 15 and the bolts 12 to prevent arcing

between said parts and the contacts 7. The 55 shield 16 carries an insulating sleeve or bushing 18 coaxially disposed with respect to the shaft 21 and bridging the space between the terminal 15 and the plate 3. Exterior to the casing 1 the shaft 21 is provided with 60 a handle 23 secured to said shaft by a set screw 20 which passes through the hub 22 of said handle and engages said shaft. When said handle is rocked it operates, through the shaft 21, to move the brush 9 over the contacts 7. To position the handle with respect to the contacts 7, a segment 25 is secured to or formed integral with the casing 1, said segment being provided with a series of recesses or indentations 27 to receive a roller 70 28 carried by a spring pressed pin 31 slidably mounted in a boss 29 formed on the handle 23.

Pivoted at 24 to the arm 13 is an arm 26 carrying at its end a roller 40. Between 75 the arm 26 and the insulating plate 17 is interposed a spring 38 tending normally to press the roller 40 toward the plate 3. The follower 34 is also preferably provided with a laterally extending lip 47 overlapping the 80 arm 26 and its spring 38 in such a manner as to protect those members from arcing between the same and the contacts 7 when the controller is operated as hereinafter described. As the shaft 21 is rotated the roller 85 40 engages successively a series of studs 42 carried by the plate 3, said studs corresponding in number and arrangement to the contacts 7, and each being connected with the adjacent contact through a blow-out coil 43. 90 The arrangement is such that, as the handle 23 is turned toward the "off" position, the roller 40 is brought into engagement with a stud 42 before the brush 9 passes out of engagement with the corresponding contact 7. 95 The circuit between the terminal 15 and contact 7 is therefore closed through the arm 26, roller 40, stud 42, and blow-out coil 43 before it is broken between said contact and the brush 9, so that no arc is drawn between 100 said brush and contact when they are separated. When the roller 40 and stud 42 are subsequently separated, the arc drawn between them is immediately extinguished by the blow-out coil 43. By this means, it will 105 be seen, any arcing incidental to the passage of the brush 9 from one contact 7 to another will take place between the roller 40 and

studs 42, rather than between the brush 9 and contacts 7, thereby preventing injury to the latter. It will also be seen that this arcing is reduced to a minimum by the action 5 of the blow-out coils 43. It will furthermore be seen that each of the blow-out coils is energized only during the separation of the corresponding connector elements, when current flow through said coil is needed to 10 extinguish an arc, so that all difficulties arising from heating or waste of current due to unnecessary current flow through the coils are avoided.

To connect the line terminal 5 with the 15 brush terminal 15, there is provided a fuse plug 35 adapted to be introduced into the hollow shaft 21 and to seat in an insulating bushing 46 therein, said fuse plug containing a suitable fuse (not shown) and having 20 a terminal 39 adapted to engage the line terminal 5, a terminal 41 adapted to engage the brush terminal 15, and a handle 57 at its outer end whereby said fuse plug may be 25 conveniently removed. The particular construction of the fuse plug per se forms no portion of the present invention and, being of a type well known in the art, this fuse plug requires no further description in detail herein.

30 This application is a division of my pending application, Serial No. 240,035, filed June 14, 1918, electrical controllers.

While I have in this application specifically described one form which my invention 35 may assume in practice, it will be understood that this form of the same is shown for purposes of illustration and that the invention may be modified and embodied in other forms without departing from its 40 spirit or the scope of the appended claims.

What I claim as new and desire to secure by Letters Patent is:

1. In an electrical controller, in combination, a series of contacts, a brush movable 45 to engage said contact members successively, and a series of supplemental contact members connected with said first named contact members respectively, said two series of contact members having their contact surfaces 50 in planes parallel to the same plane, and means moving with said brush to cause drawing of an arc only from said supplemental contact members, said means being resiliently positioned for movement in planes 55 perpendicular to said planes first mentioned.

2. In an electrical controller, in combination, a series of contacts, a brush movable to engage said contact members successively, and a series of supplemental contact members connected with said first named contact members respectively, said two series of contact members having their contact surfaces 60 in planes parallel to the same plane, and means moving with said brush to cause drawing of an arc only from said supple-

mental contact members, said means and brush being mounted for movement in planes perpendicular to said planes first mentioned.

3. In an electrical controller, in combination, a series of contacts, a brush rotatably mounted and movable successively into engagement with said contact members, and a series of supplemental contact members connected with said first named contact members respectively, said two series of contact members having their contact surfaces in planes parallel to the same plane, and means moving with said brush to cause drawing of an arc only from said supplemental contact members, said means including a roller rotatable on an axis in a plane parallel to a plane parallel to the axis of rotary movement of said brush and adapted to engage said supplemental contacts.

4. In an electrical controller, in combination, a series of contacts, a brush rotatably mounted and movable successively into engagement with said contact members, and a series of supplemental contact members connected with said first named contact members respectively, said two series of contact members having their contact surfaces in planes parallel to the same plane, and means moving with said brush to cause drawing of an arc only from said supplemental contact members, said means including a roller rotatable on an axis in a plane parallel to a plane parallel to the axis of rotary movement of said brush and adapted to engage said supplemental contacts, and supporting 90 means for said roller permitting pivotal movement thereof towards and from the contacts of said second series.

5. In an electrical controller, a plurality of contacts connected to each other, a contact member movable over said contacts to progressively vary the resistance of a circuit, a plurality of supplemental contacts engageable with said contact member, means for transferring current carried by one of the main contacts to a supplemental contact when said member is moved in a direction to effect an increase of resistance, and means for extinguishing an arc at said supplemental contact.

6. In an electrical controller, a series of contacts, a contact member movable over said contacts to progressively vary the resistance of a circuit, a corresponding series of supplemental contacts engageable with said contact member, and means including a blow out coil for conducting current through one of said supplemental contacts when said contact member leaves a corresponding one of the main contacts, said coil being arranged adjacent said supplemental contact to extinguish an arc when said member leaves the same.

7. In an electrical controller, a plurality of main contacts, a controller arm having 120

a brush adapted to successively engage said contacts to progressively vary the resistance of a circuit, a plurality of supplemental contacts one of the same being electrically connected to each of the main contacts, means carried by said controller arm to establish flow of current through a supplemental con-

tact before said brush leaves the corresponding main contact, and a blow out coil adjacent each of said supplemental contacts for extinguishing an arc.

In testimony whereof I affix my signature.

CHARLES W. WYMAN.
